UNITED STATES PATENT OFFICE.

THEODORE WEISBERGER, OF NORTH YAKIMA, WASHINGTON.

STOVE OR FURNACE.

1,152,363.

Specification of Letters Patent. Patented Aug. 31, 1915.

Application filed January 23, 1914. Serial No. 813,916.

To all whom it may concern:

Be it known that I, THEODORE WEISBERGER, a citizen of the United States, residing at North Yakima, in the county of 5 Yakima and State of Washington, have invented certain new and useful Improvements in Stoves or Furnaces; and I do hereby declare the following to be a full, clear, and exact description of the invention, such as 10 will enable others skilled in the art to which it appertains to make and use the same.

My invention relates to improvements in stoves or furnaces for heating or cooking purposes, and especially to that class of 15 stoves known as magazine stoves adapted to burn soft or bituminous coal, in which the magazine is charged nearly to the top with fuel, and fire burns from the base of the charge; the rising gases passing through 20 the fuel being conducted downward through suitable passages, and being drawn along with the incoming air through said passages down, through and across the incandescent fuel into a heating chamber, whence it is 25 drawn upward through said chamber and through suitable flues to the smoke pipe under the natural draft of said pipe.

The invention is especially intended to provide an apparatus in which the fuel is 30 automatically fed toward the back of the fire-pot, and in which the major portion of the mixed air and hydrocarbon gases are brought down to the rear of the fire-pot and are carried from the incandescent fuel to 35 the front, whereby the green fuel has its volatile gases carried forward through the incandescent fuel in the front of the fire-pot, and complete combustion is secured. The 40 products of combustion passing forward through the fire-pot are then caused to pass over a deflector, which tends to throw the heat downward in front of the stove, causing a wide angle of dispersion of the heat rays. To prevent ignition of the fuel in the 45 upper portion of the magazine I provide suitable insulating material, such as fire bricks, or the like. In the bottom of the fire-pot, I provide suitable grates, preferably of the dumping type so that the ashes 50 may be expelled as the charge of fuel in the magazine settles downward.

According to my present invention I provide a heating chamber in front of the fire-pot which projects downward, and is separated from the ash-pit by an air space with an open air passage between the two, so that

the air passing through said space may be heated and increase the radiation surface of the stove. Moreover, I preferably provide a straight front to the stove, which is heated 60 from top to bottom by the products of combustion from the fire-pot.

In the usual method of constructing stoves, the lower portion of the stove is entirely devoted to the ash-pit, which has practically no heat radiating surface whatsoever. Above this is the grate, and above this is the fire-pot, the result being that the heating portion of the stove is at a considerable distance from the base thereof, with the result 70 that a large portion of the surface of the stove which might be made effective for radiating purposes is practically useless; but according to my invention I arrange the heating chamber in such a way that the entire 75 face and sides thereof are efficient heat radiating surfaces, while the back of the bottom also transmits heat to the air passing behind the same, while even the bottom of this heating chamber also is heated and 80 serves to heat the air currents adjacent to same.

My improved magazine may be applied not only for use in connection with heating stoves, but also for use in connection with 85 cooking stoves, or furnaces, for hot water or steam heating.

These and other features of my improved construction will be more fully understood after reference to the accompanying drawings, in which similar parts are indicated by similar reference symbols throughout the 90 several views.

Figure 1 shows a front elevation of my improved heating stove, and showing the 95 door or front wall of the right-hand side thereof removed, and showing the parts broken away, and parts in section; Fig. 2 shows a central vertical section along the line 2—2 of Fig. 1, and looking in the direction of the arrows; Figs. 3 and 4 show, respectively, sections along the lines 3—3 and 4—4 of Fig. 2, and looking down; Fig. 5 shows a section through the grate, the same being on an enlarged scale, and also shows 100 in dotted lines the gears for dumping the grate; Fig. 6 shows a central vertical section through one of the grate members shown in Fig. 5; Fig. 7 shows in section a modified form of the deflector used instead 110 of the water-back of Figs. 1-3; Fig. 8 is a similar view to Fig. 2, showing as a modifi-

cation a simplified arrangement for conducting the incoming air and the rising gases down from the top of the stove, wherein the back of the stove forms the rear wall of the air passage; Fig. 9 shows a section along the line 9—9 of Fig. 8, and looking down; Fig. 10 is a perspective view of the inner portions of the heating stove shown in Figs. 1—3, but with the addition of dampers for controlling the side passages provided for the upward movement of the products of combustion; and Fig. 11 shows the improved magazine of Figs. 1—3 and 10 as reversed and applied to a cooking stove. This figure shows the magazine in a similar section to that of Fig. 2, but reversed and connected to a cooking stove, shown in central vertical section.

Referring first to Figs. 1—6, A represents the fire pot below the magazine whose top is closed by a door A' provided with the register, or valve, α , which door is hinged, as at α' , and is provided with an outwardly-projecting rib α^s which swings in the grooved recess α^s mounted at the top of the plate A³, and thus keeps this clean of ashes, coal dust, and the like, thus automatically protecting the hinge from clogging up with coal dust when the magazine is being charged with fuel.

The magazine is provided with interior walls A² and A³, and with the outer walls A⁴ and A⁵, and with the end walls A⁶, the lower portion of which end walls A⁶ is preferably made renewable, so as to be renewed when burned out. The wall A³ is tapered outward as at α^3 and terminates in a suspended vertical grate α^4 , having passages therethrough between vertical bars. This grate is bent at an angle α^5 terminating the inclined face α^3 .

The outer shell of the stove is composed of the side walls A⁰, A⁷ and A⁸, and the front plate A⁹. The front plate and sides of the stove may be made either of metal, or of isinglass, as desired. The shape of the stove is preferably rectangular in cross section, though the same may have one or more of its sides curved, rounded, or of any desired shape.

In the lower portion of the magazine the grate bars B are mounted, which are preferably composed of a series of cam-shaped disks B² slid over the squared portion of the shafts B', as shown in Figs. 5 and 6. One end of each of these shafts is reduced, as at b' , to slip through the openings in the center of the plates B² and to be journaled in the plates A⁷ and A⁸. The last one of these plates B² may be locked to the shaft B' in any convenient way, as by the pin b^4 . This shaft is journaled near its other end, as at b^2 , in the plate A⁷, and is provided with a squared end b^3 , to which may be attached the handle B³ for rocking the said shaft,

and through the gearing hereinafter to be described for simultaneously rocking the shaft of the other grate member.

Mounted between the plates A⁶ and A⁷ are the gear wheels H and H', which are connected to the corresponding shafts B' in any convenient way, as by the cotter pins b^0 . These gear wheels have meshing teeth h , which terminate in the blanks h' , see Fig. 5, and thus permit the grate bars to be rocked through the desired angle in one direction, and to be automatically prevented from turning too far in the reverse direction, as shown in Fig. 5. Below the grate bars a removable ash pan C is mounted.

The front portion of the stove comprises a heating chamber D, having the front plate A⁹ and the side plates A⁷ and A⁸ either of metal or isinglass, or both, as may be desired. These front and side plates preferably extend from the top to the bottom of the stove, and the bottom of this chamber D is closed by the bottom wall D' and the inclined rear wall D² terminating just below and supporting the short comb-like grate D³. In this heating chamber D is mounted a deflector E which is shown as a water-back in which water flows through the inlet pipe E', and escapes out of the outlet pipe E², see Fig. 2, for heating or culinary purposes. This deflector has a curved or straight inclined overhanging face e' .

On the top of the deflector E I provide a shelf e^2 to support the loose fire brick F, used to keep the heat from the magazine. In the interior of the water-back is a plate e, leaving a water passage e^0 at one end for the passage of the water from the lower side of said plate to the upper side thereof, as shown in Fig. 1. This deflector E preferably extends entirely across the interior of the chamber D between the outer walls A⁷ and A⁸, and is carried by brackets e^3 cast on said walls.

The operation of the device shown in Figs. 1—6 is as follows:—Referring to Fig. 2, the fire is laid as follows:—Fill the fire-pot full of coal up to the inverted funnel-shaped mouth of the magazine, then lay on the kindling wood with paper, waste, or other material, to ignite same, then set fire to same from above, and there will be a down draft through the fuel through the open space 7 in the front of the fire-pot into the heating chamber D. The incoming air passes through the register α and down through the throat of the magazine and through the fuel, and is drawn up again through the chamber D and the side passages 8 and 9 to the flue 10, and thence through the opening 11 into the smoke pipe 12. After the fire is started, the magazine is charged with fuel up to the bottom of the openings 2 and 4, and the incoming air now passes down through the passages 3 and 5 between the walls A² and

A⁵ and the walls A³ and A⁴, respectively. Mingled with this air are any volatile gases which rise from the fuel in the magazine, and these are brought down to the top and back of the fire. The amount of air passing forward through the opening 2 and down through the passage 3 to the top of the fire is controlled by any suitable register 2^a. The major portion of the air with the com-
5 mingled gases is caused to pass to the rear of the fire pot through the opening 4 and the passage 5, and through the opening 6 in the vertical grate a⁴, and enters the burning fuel in the fire pot.

15 The front wall of the mouth of the magazine is preferably straight, while the rear wall is inclined in the form of an inverted funnel, as at a³, so that any swelling of the fuel due to the coking of same as it is heated
20 will not choke the outlet of the throat of the magazine, and interfere with the free downward movement of the superposed fuel therein. Moreover by having this inclined face in rear of the throat of the magazine,
25 there will be a tendency of the green fuel to fall backward and feed to the back of the fire pot in front of the vertical grate a⁴. Now the air and gases passing through this
30 grate will strike this green fuel and the combustion will be progressive until the products of combustion will escape through the incandescent fuel at the front of the fire-box, thus insuring perfect combustion and intense heat at the front of the fire. The front
35 of the fire, which constitutes the primary radiation surface, is intensely hot, while the back of the fire is comparatively cool. Parts of the products of combustion, together with part of the radiant heat, will be deflected by
40 the curved surface e' of the deflector E, and will heat the whole front and bottom of the heating chamber D, thus giving a very wide angle of dispersion of the heat rays from the front of the furnace, and at the same
45 time providing a very large radiating surface for the heating chamber D. Thus it will be seen that the part E not only serves to deflect the products of combustion, but also to reflect downward and outward a
50 material part of the radiant heat. The radiating surface of the heating chamber D comprises not only the top, side walls, and front, but also the bottom D', and the inclined wall D², back of which the air tends
55 to pass through the opening D⁰ which is spaced away from the ash-pit so that practically no heat is wasted in heating up the ash-pit, but an increased radiating surface is secured by said construction.

60 Thus, it will be seen that I provide a very wide angle of dispersion of the heat rays, and a very large radiating surface for the heat. Moreover, by this construction the heat radiating surfaces of the heating chamber D are near the floor of the room, where

the air is normally coldest, and thus convection currents are started near the floor of the room.

After passing upward through the chamber D, the products of combustion are carried through the side passages 8 and 9 to the flue 10, and thence escape through the outlet 11 into the smoke pipe 12, where they are carried off by the natural draft. The escape of the products of combustion through these side passages 8 and 9 may be controlled, if desired, by a suitable damper arrangement, such as that shown in Fig. 10, in which I, I,
70 are two dampers rigidly attached to the shaft I', preferably counterbalanced by the weights I². This shaft may be rocked, and the dampers controlled by turning the hand wheel I³. These dampers are supplemented by plates I⁴, fitting in the passages between the tile F and the outer walls of the stove,
75 80 and furnishing supports for the shaft I'.
85

If the dampers are turned to the horizontal position this will virtually close the passage for the gases beneath the ends of the deflector through the passages 8 and 9, and all the products of combustion will pass above said deflector and over said dampers into the upper portions of the passages 8 and 9, and thence to the flue 10 and out through the smoke pipe; but if the dampers
90 are turned to the vertical position this will close the passage for the products of combustion through said passages 8 and 9 above the deflector E, but will leave the passage for said products of combustion open beneath said deflector E, and back of the dampers, so that these products of combustion may be caused either to escape from the top of the chamber D, or from the bottom of the chamber, as may be preferred; or the relative amount of the products of combustion passing above or below the deflector E may be regulated by adjustment of the dampers aforesaid. Air may also be let into the bottom of the furnace in the usual way through
95 100 the door C' of the ash-pit shown in Fig. 1, but this will rarely be required.

In place of the water-back constituting the deflector E shown in Fig. 2, a solid deflector made of fire clay, or other suitable material, such as E⁰ in Fig. 7, may be used if desired.

In the modification shown in Figs. 8 and 9, the walls A⁴ and A⁰ of Fig. 2 are combined in one, and the down draft coming through the register a enters the opening a¹⁰, passes down the opening a¹¹ at the back of the magazine, and then flows into the combustion chamber above the dumping grate, through the opening 6 shown in Fig. 120 2. The products of combustion pass from the combustion chamber into the front chamber D as before, and then pass upward through the side passages 8 and 9, and the openings a¹² into the flue a¹³, which is con-
125 130

nected to the smoke pipe 12. Thus the flow of the gases is substantially the same as before, but there is a slight simplification of construction in the rear portion of the stove.

5 In both cases, there is a down draft at the rear of the magazine which passes through the fuel forward and upward, as above explained.

In the adaptation of the magazine to a 10 cooking stove, shown in Fig. 11, the front portion of the heating stove is removed entirely, and the magazine is turned through 180° to connect with the open end of the cooking stove K, which is provided with the ordinary, or any suitable, oven K', with air passages, k, k', k², k³ and k⁴ for conducting the heated products of combustion up and around the oven, and then into the side passages k⁴ and up to the smoke pipe L, which 15 is controlled by the damper L'. This cooking stove is preferably provided with an auxiliary grate M mounted on a shaft m, and adapted to be rocked down against the bumper M' when it is desired to dump the 20 grate.

The construction of the other grate members is similar to that already described. In this form of device, there is a down draft through the side passages 3 and 5 of the 25 magazine which flows into the back and top of the fuel, and instead of passing into the front heating chamber D, as shown in Fig. 2, the products of combustion flow into the upper passage k of the cooking stove, as already described.

In order to prevent the front wall of the oven from being burnt out, a removable false front k⁰ may be provided, which can be removed when worn out. In this modification, I have shown a slightly different handle a¹⁴ from that shown at a¹⁵ in Figs. 2 and 8, for turning the register a and for lifting the door A'.

I do not intend to limit the invention to 45 use with any particular kind of heating or cooking stove; as it may be applied to various kinds of such stoves, as also to steam and water heaters.

It will be obvious that various modifications might be made in the herein described 50 apparatus and in the construction, combination and arrangement of parts which can be used without departing from the spirit of my invention.

55 Having thus described my invention, what I claim and desire to secure by Letters Patent of the United States is:—

1. A combustion apparatus for stoves or 60 furnaces, comprising a fire pot having plane parallel sides and an opening in the front wall thereof, a magazine above said fire pot inclined rearward near its base, an air inlet in the top of said magazine, a vertical grate mounted across the rear of said fire pot below 65 said magazine and extending entirely

across the rear end of the fire pot between said parallel sides, and front and back walls spaced away from said magazine to form downwardly-directed air passages for the front and top of the fire pot, and to the rear thereof, respectively, said back wall being inclined rearward corresponding to the rearward incline of the base of the magazine, in combination with a heating chamber mounted in the front of said fire pot and receiving the products of combustion through the opening in the front wall thereof, said heating chamber being provided with flue connections to the smoke pipe, substantially as described. 70

2. A combustion apparatus for stoves or furnaces, comprising a fire pot having an opening in the front wall thereof, a magazine above the same and inclined rearward near its base, an air inlet in the top of said magazine, a vertical grate mounted at the rear of said fire pot below said magazine, and front and back walls spaced away from said magazine to form downwardly-directed air passages to the front and top of the fire 80 pot, and to the rear thereof, respectively, said back wall being inclined rearward and corresponding to the rearward incline of the base of the magazine, in combination with a heating chamber mounted in front of said fire pot, and receiving the products of combustion through the opening in the front wall of the fire pot, said heating chamber being provided with flue connections to the smoke pipe, with a deflector having an inclined lower face and a reversely inclined upper face terminating in a shelf, said deflector extending across said heating chamber above said fire pot, with heat insulating material mounted on said shelf, substantially as described. 85

3. The combination with a magazine stove having a fire-pot opening in the front thereof, and means for supplying air to the rear of said fire-pot, and an ash pit located below said fire-pot, of a rectangular heating chamber mounted in front of said fire-pot and receiving the products of combustion therefrom, said heating chamber projecting downwardly below the opening in said fire-pot and being separated from said ash pit by an air space, and a deflector projecting into said heating chamber and located above the opening in said fire-pot and adapted to reflect the heat rays downward into the lower portion of said heating chamber, with means for carrying the products of combustion from said heating chamber to the flue, substantially as described. 105

4. The combination with a magazine stove having a fire pot opening in the front thereof, of a rectangular heating chamber mounted in front of said fire pot and receiving the products of combustion therefrom, said heating chamber projecting downwardly be- 110 115 120 125 130

low the opening in said fire pot, and a curved deflector projecting into said heating chamber and located above the opening in said fire pot, with side passages connecting said heating chamber with the smoke stack, and dampers mounted in said side passages and adapted to throw the products of combustion above or below said curved deflector as desired, substantially as described.

10 5. A combustion apparatus for stoves or furnaces, comprising a fire pot having an opening in the front wall thereof, a magazine above said fire pot inclined rearward near its base, an air inlet in the top of said magazine, a vertical grate mounted across the rear of said fire pot below said magazine and extending entirely across the rear end of the fire pot between said parallel sides, and front and back walls spaced away from 20 said magazine to form downwardly-directed air passages for the front and top of the fire pot, and to the rear thereof, respectively, in combination with a heating chamber mounted in the front of said fire pot and receiving the products of combustion through the opening in the front wall thereof, said heating chamber being provided with flue connections to the smoke pipe, substantially as described.

25

6. A combustion apparatus for stoves or 30 furnaces, comprising a fire pot having an opening in the front wall thereof, a magazine above said inclined rearward near its base, an air inlet in the top of said magazine, a vertical grate mounted at the rear 35 of said fire pot below said magazine, and front and back walls spaced away from said magazine to form downwardly-directed air passages to the front and top of the fire pot, and to the rear thereof, respectively, 40 in combination with a heating chamber mounted in front of said fire pot, and receiving the products of combustion through the opening in the front wall of the fire pot, said heating chamber being provided with 45 flue connections to the smoke pipe, with a deflector having an inclined lower face and a reversely inclined upper face, said deflector extending across said heating chamber above said fire pot, substantially as 50 described.

In testimony whereof, I affix my signature, in presence of two witnesses.

THEODORE WEISBERGER.
